UNITED STATES PATENT OFFICE

GEORGE P. WIGGINTON, OF KALAMAZOO, MICHIGAN, ASSIGNOR TO KALAMAZOO LOOSE LEAF BINDER CO., OF KALAMAZOO, MICHIGAN.

BINDER DEVICE.

1,266,648.

Specification of Letters Patent. Patented May 21, 1918.

Original application filed November 26, 1915. Serial No. 63,566. Divided and this application filed October 1, 1917. Serial No. 194,163.

To all whom it may concern:

Be it known that I, GEORGE P. WIGGINTON, a citizen of the United States, residing at the city and county of Kalamazoo, State of Michigan, have invented certain new and useful Improvements in Binder Devices, of which the following is a specification.

This invention relates to improvements in binder devices.

10 This application is a division of my application filed November 26, 1915, Ser. No. 63,566.

The main objects of this invention are:

First, to provide an improved binder device which facilitates the use of temporary binders or loose sheet holders, particularly such as are used for record or accounting purposes.

Second, to provide an improved binder device which facilitates the manipulation and handling of temporary binders or loose sheet holders for the insertion or removal of sheets.

Third, to provide an improved binder which facilitates the handling or manipulation of the sheets of temporary binders or loose sheet holders.

Further objects, and objects relating to structural details, will definitely appear from the detailed description to follow.

I accomplish the objects of my invention by the devices and means described in the following specification. The invention is clearly defined and pointed out in the claims.

35 A structure which is a preferred embodiment of my invention is clearly illustrated in the accompanying drawing, forming a part of this specification, in which:

Figure I is a perspective view of a holder device embodying the features of my invention.

Fig. II is a perspective view with a binder arranged therein in position for the manipulation of the sheets.

45 Fig. III is a plan view partially in section on a line corresponding to the broken line 3-3 of Fig. IV, a part of the sheets being shown in offset relation.

Fig. IV is a vertical longitudinal section

on a line corresponding to line 4-4 of Fig. III.

Fig. V is a detail vertical section corresponding to that of Fig. IV showing the holder adjusted to position to receive a binder and with the binder arranged thereon. 55

Fig. VI is a detail longitudinal section on a line corresponding to line 6-6 of Fig. III, showing the relation of the removable post in the binder.

Fig. VII is a detail section through the 60 post holder on a line corresponding to line 7-7 of Fig. IV.

Fig. VIII is an enlarged detail section on a line corresponding to line 8-8 of Fig. IV, showing details of the guide member. 65

Fig. IX is a detail longitudinal section through the binder illustrated removed from the holder and closed.

In the drawing similar reference characters refer to similar parts throughout the 70 several views, and the sectional views are taken looking in the direction of the little arrows at the ends of the section lines.

Referring to the drawing, the binder illustrated comprises a pair of covers 1 provided 75 with chambers to receive the adjusting mechanism. Binding strips 2 extend between the covers. Clamping members 4 are pivotally connected to the covers. These clamping members have sockets 5 for the removable 80 posts 6. The sheets or leaves 7 have holes 8 adapted to receive these posts and notches 9 adapted to receive the binding strips. When the binder is closed with the posts inserted the sheets are effectively retained in the 85 binder. However, when the clamping members are separated and the posts removed the sheet body is entirely free.

The binder and sheets illustrated are described in detail in my Letters Patent 90 #1,174,458, issued to me March 7, 1916.

I provide a pair of holders each adapted to receive a binder member comprising, in the structure illustrated, the cover and clamping bar, and support the same so that 95 the sheets may be arranged thereon.

These holders, which I designate generally by the numerals 10 and 11 in Fig. I of the

drawing, are mounted on a pair of supporting base members 12. The holder 10 comprises side member 13 and an end member 14, while the holder member 11 comprises 5 a side member 15 and an end member 16. The end members are mounted in a relatively fixed relation with their upper edges meeting. The end members have registering slots 17 adapted to receive the binding strips 10 2 when the binders are arranged as shown in Fig. II. The side members are mounted on pivots 18 so that they may be swung to coacting relation with the end members, as best shown in Fig. VI, or to an approximately horizontal position, as shown in 15 Fig. V.

The side members are adjustably supported by the slotted links 19 which are connected to the inner ends of the side members 20 at 20—20, and have teeth 21 adapted to engage the bolts 22. The bolts are provided with clamping nuts 23 for securing the links in their adjusted position. With the parts 25 thus arranged, the side members of the holders may be swung to their horizontal position to receive the binder members in arranging the binder in the holder or swung into position to coact with the end members and the inner ends of the sheets adjusted 30 against the end members of the holders, as shown in Fig. VI.

The end members of the holders are preferably arranged so that the end member 14 is at right angles to the side member 13 35 when it is adjusted to its lower position, thereby assisting in alining the sheets to receive the post. The end member 16 is preferably disposed at an acute angle to its coacting side member, as shown in Fig. IV, 40 so that when the sheets are adjusted on the holder the outer ends are adjusted in a stepped or fanned relation to facilitate the fingering of the sheets.

To assist in alining the slots and holes in 45 the sheets I provide the end member 14 with a guide 24, the end member 16 with a guide 25, the notch of the sheets being adapted to be engaged with these guides. The guide 24 is made removable so that it may be re- 50 moved to permit the adjustment of the binder members for closing the binders. To facilitate this the end member 14 is provided with a slot at 26 and provided with a pair of slide plates 27 for the slide 28 secured to the 55 guide so that it may be inserted and removed by longitudinal movement.

The guide is also preferably adapted as a gage, being provided with a scale 29 having indicia thereon indicating the proper length 60 of post to be used, that is, the thickness of the sheet body, as indicated by the scale, indicates the proper length of post.

To further facilitate the selection of posts mount a holder 30 having pockets 31 for

posts of different lengths. This holder is 65 mounted on the back of the holder side member 15. The pockets are provided with indicia 32 corresponding to the indicia of the guide 24.

With the parts thus arranged the sheets 70 may be readily disposed on one of the binder members, either in alined body or with part of the sheets offset, and they are guided so that the removable posts may be readily inserted and the binding strips swung into 75 the slots. When one binder member is adjusted upon the other the guide 24 is removed so as not to interfere with the alining of the same thereon.

My improved binder greatly facilitates 80 the use of temporary binders for the keeping of records, particularly where it is desired to keep such records on typewriting machines or accounting machines. It is, however, advantageous when it is desired to 85 keep the records by hand.

The sheets are supported so that they are readily accessible and the wear and tear on the sheets in handling is minimized.

I have illustrated and described my improvements in a practical embodiment. I have only shown one type of binder, but it will be understood that other types, for instance, the post type shown in my said patent, may be effectively used. I have not 90 attempted to illustrate or describe various modifications in structural details which I contemplate as I believe the disclosure made will enable those skilled in the art to which this invention relates to embody or adapt 95 the same as may be desired.

Having thus described my invention, what I claim as new and desire to secure by Letters Patent, is:—

1. In a device of the class described, the 105 combination of a pair of holders each comprising side and end members disposed with their end members adjacent, said end members having alined binding strip openings 110 therein, said side members being adjustably mounted so that they may be adjusted to substantially horizontal positions or into position to coact with said end members, alined guide members on said end members, one of said guide members being removably mounted 115 and provided with indicia, a post holder having pockets provided with indicia corresponding to the indicia of said removable guide member, separably associated binder members comprising covers, clamping members pivotally connected to said covers, said clamping members having opposed post sockets in their inner sides, binding strips extending between said binder members, binding posts of different lengths adapted 120 to be removably engaged in said sockets or arranged in said holder, and sheets provided with a plurality of uniformly 125

spaced notches open at their binding edges and a plurality of holes adjacent their binding edges uniformly spaced with each other and with said notches, so that there are registering notches alined with said openings in said end members and registering notches adapted to be engaged with said guide members, and registering holes, when said sheets are arranged in an alined body or in a laterally offset relation upon the binder members arranged in said holders.

2. In a device of the class described, the combination of a pair of holders comprising side and end members disposed with their end members adjacent, said end members having alined binding strip openings therein, said side members being adjustably mounted so that they may be adjusted to substantially horizontal positions or into position to coact with said end members, alined guide members on said end members, separably associated binder members comprising covers, clamping members pivotally connected to said covers, said clamping members having opposed post sockets in their inner sides, binding strips extending between said binder members, binding posts of different lengths adapted to be removably engaged in said sockets, and sheets provided with a plurality of uniformly spaced notches open at their binding edges and a plurality of holes adjacent their binding edges uniformly spaced with each other and with said notches so that there are registering notches alined with said openings in said end members and registering notches adapted to be engaged with said guide members, and registering holes, when said sheets are arranged in an alined body or in a laterally offset relation upon the binder members arranged in said holders.

3. In a device of the class described, the combination of a pair of holders each comprising side and end members disposed with their end members adjacent, said end members having alined binding strip openings therein, alined guide members on said end members, one of said guide members being removably mounted and provided with indicia, a post holder having pockets provided with indicia corresponding to the indicia of said removable guide member, separably associated binder members comprising covers, clamping members pivotally connected to said covers, said clamping members having opposed post sockets in their inner sides, binding strips extending between said binder members, binding posts of different lengths adapted to be removably engaged in said sockets or arranged in said post holder, and sheets provided with a plurality of uniformly spaced notches open at their binding edges and a plurality of holes adjacent their binding edges uniformly spaced with each

other and with said notches so that there are 65 registering notches alined with said openings in said end members and registering notches adapted to be engaged with said guide members, and registering holes, when said sheets are arranged in an alined body 70 or in a laterally offset relation upon the binder members arranged in said holders.

4. In a device of the class described, the combination of a pair of holders each comprising side and end members disposed with 75 their end members adjacent, said end members having alined binding strip openings therein, said side members being adjustably mounted so that they may be adjusted to substantially horizontal position or into position to coact with said end members, a guide member removably mounted on one of said end members and provided with leaf body gaging indicia, a holder for posts of different lengths provided with indicia corresponding to the indicia of said guide member, separately associated binder members, binding strips extending between said binder members, binding posts of different lengths adapted to be removably associated 90 with said binder members, and sheets provided with a plurality of uniformly spaced notches open at their binding edges and a plurality of holes adjacent their binding edges uniformly spaced with each other and 95 with said notches so that there are registering notches alined with said openings in said end members and registering notches adapted to be engaged with said guide member, and registering holes, when said sheets are 100 arranged in an alined body or in a laterally offset relation upon the binder member arranged in said holder having said guide member.

5. In a device of the class described, the 105 combination of a pair of holders each comprising side and end members disposed with their end members adjacent, said end members having alined binding strip openings therein, a guide member mounted on one of 110 said end members and provided with leaf body gaging indicia, a holder for posts of different lengths provided with indicia corresponding to the indicia of said guide member, separately associated binder members, 115 binding strips extending between said binder members, binding posts of different lengths adapted to be removably associated with said binder members, and sheets provided with a plurality of uniformly spaced notches 120 open at their binding edges and a plurality of holes adjacent their binding edges uniformly spaced with each other and with said notches so that there are registering notches alined with said openings in said end members and registering notches adapted to be engaged with said guide member and registering holes, when said sheets are arranged 125

in an alined body or in a laterally offset relation upon the binder member arranged in said holder having said guide member.

6. In a device of the class described, the combination of a pair of holders each comprising side and end members disposed with their end members adjacent, said end members having alined binding strip openings therein, said side members being adjustably mounted so that they may be adjusted to substantially horizontal positions or into position to coat with said end members, a guide member removably mounted on one of said end members, separably associated binder members, binding strips extending between said binder members, binding posts of different lengths adapted to be removably associated with said binder members, and sheets provided with a plurality of uniformly spaced notches open at their binding edges and a plurality of holes adjacent their binding edges uniformly spaced with each other and with said notches so that there are registering notches alined with said openings in said end members and registering notches adapted to be engaged with said guide member, and registering holes, when said sheets are arranged in an alined body or in a laterally offset relation upon the binder member arranged in said holder having said guide member.

7. In a device of the class described, the combination of a pair of holders each comprising side and end members disposed with their end members adjacent, said end members having alined binding strip openings therein, a guide member mounted on one of said end members, separably associated binder members, binding strips extending between said binder members, binding posts of different lengths adapted to be removably associated with said binder members, and sheets provided with a plurality of uniformly spaced notches open at their binding edges and a plurality of holes adjacent their binding edges uniformly spaced with each other and with said notches so that there are registering notches alined with said openings in said end members and registering notches adapted to be engaged with said guide member, and registering holes, when said sheets are arranged in an alined body or in a laterally offset relation upon the binder member arranged in said holder having said guide member.

8. In a device of the class described, the combination of a pair of holders each comprising side and end members disposed with their end members adjacent, said end members having alined binding strip openings therein, said side members being adjustably mounted so that they may be adjusted to substantially horizontal positions or into position to coat with said end members, sepa-

rably associated binder members, and binding strips extending between said binder members.

9. In a device of the class described, the combination of a binder comprising separably associated binder members, and a pair of holders each comprising side and end members, the side members being mounted so that they may be adjusted to substantially horizontal positions or to an inwardly inclined relation coacting with said end members and the binder members supported thereon in either position.

10. In a device of the class described, the combination of a pair of holders each comprising side and end members, one of said holders being provided with sheet body gaging indicia, a holder for posts of different lengths provided with indicia corresponding to the indicia of said holder, separably associated binder members, and binder posts of different lengths adapted to be removably engaged with said binder members.

11. In a device of the class described, the combination of a binder provided with interchangeable binding posts of different lengths, a support adapted to receive the binder in open position with sheets arranged thereon, said support being provided with gaging indicia for the sheet body indicating posts suitable therefor, and a holder for posts of different lengths provided with indicia corresponding to the indicia of said support.

12. In a device of the class described, the combination of a binder provided with interchangeable binding posts of different lengths, and a support adapted to receive the binder in open position with sheets arranged thereon, said support being provided with gaging indicia for the sheet body indicating posts suitable therefor.

13. In a device of the class described, the combination with loose sheets and binding means therefor comprising posts of different lengths, a support adapted to receive said sheets and binding means, said support being provided with gaging indicia for the sheets indicating posts suitable therefor, and a holder for posts of different lengths, provided with indicia corresponding to the indicia of said support.

14. In a device of the class described, the combination with loose sheets and binding means therefor comprising posts of different lengths, and a support adapted to receive said sheets and binding means, said support being provided with gaging indicia for the sheets indicating posts suitable therefor.

15. In a device of the class described, the combination of a binder comprising a pair of separably associated binder members, holders for said binder members each comprising side and end members, and means for ad-

justably supporting one side member so that it may be adjusted to a substantially horizontal position or to an inwardly inclined coacting relation to said end member to provide a trough-shaped holder.

16. In a device of the class described, the combination of a binder comprising separably associated binder members, and a binder member holder comprising side and end members, the side member being adjustable relative to the end member so that

it may be adjusted to a substantially horizontal position or to an inwardly inclined coacting relation to said end member to provide a trough-shaped holder.

15.

In witness whereof, I have hereunto set my hand and seal in the presence of two witnesses.

GEORGE P. WIGGINTON. [L.S.]
